I claim the ornamental design for a translucent bar cup with measuring lines, as shown and described.

DESCRIPTION

FIG. 1 is a perspective view of a first embodiment of a translucent bar cup with measuring lines showing my new design; FIG. 2 is a front elevational view thereof; FIG. 3 is a rear elevational view thereof; FIG. 4 is a left side elevational view thereof; the right side elevational view being a mirror image thereof FIG. 5 is a top view thereof; FIG. 6 is a bottom view thereof; FIG. 7 is a perspective view of a second embodiment of a translucent bar cup with measuring lines; FIG. 8 is a front elevational view thereof; FIG. 9 is a rear elevational view thereof; FIG. 10 is a left side elevational view thereof; the right side elevational view being a mirror image thereof; FIG. 11 is a top view thereof; FIG. 12 is a bottom view thereof; FIG. 13 is a perspective view of a third embodiment of a translucent bar cup with measuring lines; FIG. 14 is a front elevational view thereof; FIG. 15 is a rear elevational view thereof; FIG. 16 is a left side elevational view thereof; the right side elevational view being a mirror image thereof; FIG. 17 is a top view thereof; and, FIG. 18 is a bottom view thereof.
